UNITED STATES PATENT OFFICE

HENRY JOSEPH ROUND, OF LONDON, ENGLAND, ASSIGNOR TO RADIO CORPORATION OF AMERICA, A CORPORATION OF DELAWARE

THERMIONIC VALVE

Application filed September 7, 1928, Serial No. 304,480, and in Great Britain September 23, 1927.

This invention relates to thermionic valves, and more particularly to the so-called "screened grid" thermionic valves in which an electrostatic screen is interposed between 5 an input electrode and an output electrode.

According to this invention a thermionic valve is provided with two or more electrostatic screens interposed between an input and an output electrode of the valve.

10 The invention is illustrated in the accompanying drawing in which;

Figure 1 shows a valve constructed in accordance with my invention while:

15 Figure 2 shows a modification of the valve of Figure 1.

Referring first to Figure 1, which shows one form of construction, a thermionic valve comprises five transversely arranged electrodes, namely, a filament 1, a control grid 2 formed as a flattened helix surrounding the filament, an anode 3 and two electrostatic screening grids 4 and 5, arranged one behind the other between the control grid and the anode. The screening grids are formed 25 of open mesh, the grid 5 being provided with an annular flange in part enclosing the anode.

In operation the screening grids, which preferably extend substantially to the walls of the valve, are connected to suitable sources 30 of static voltage such as batteries through non-inductive connections whereby they are maintained at definite constant potentials, but will be at zero potential. In the arrangement shown in Figure 1, the filament, control 35 grid and the screening grid 4 are "stemmed" to one footstep 6 of the valve, which is formed double-ended, the screening grid 5 and the anode being "stemmed" to the other footstep 7.

40 In the modification shown in Figure 2, a second control grid 8 is connected in parallel with the control grid 2 normally provided and is located between the two screening grids. In operation the control grids are 45 maintained with negative potential "bias" and the screening grids with positive potential "bias". In the arrangement shown in Figure 2, the additional control grid 8 is stemmed at one end of the valve, together 50 with the filament 1, control grid 2 and first

screening grid 4, the screen screening grid 5 and anode 3 being stemmed at the other end of the valve.

In Figure 2 the control grids are shown as constituted each by parallel wires stretched 55 across a hoop, but obviously any other convenient form of grid may be employed.

If desired more than two screening grids and more than two control grids may be provided, the additional control grids being in 60 general sandwiched between pairs of screening grids.

Having now particularly described and ascertained the nature of my said invention and in what manner the same is to be performed, what I claim is:

1. A thermionic valve comprising an envelope enclosing a cathode, two parallel control grids connected together within said envelope, two separate electrostatic screens, and an anode, 70 one of said screens being located between the control grids, and the other between the anode and the control grid nearest adjacent thereto.

2. A thermionic tube comprising an envelope enclosing a cathode, an anode, two parallel grid electrodes interposed between said cathode and anode and connected together inside said envelope, and two separate electrostatic screens parallel to said grid electrodes, one of said screens being interposed 80 between said connected grid electrodes and the other screen adjacent said anode.

3. A thermionic tube comprising an envelope enclosing a cathode, an anode, two 85 parallel grid electrodes interposed between said cathode and anode and connected together inside said envelope, and two separate electrostatic screens parallel to said grid electrodes, one of said screens being interposed between one of said grid electrodes and said anode, and the other screen being adjacent the other of said grid electrodes.

4. A thermionic tube comprising an envelope enclosing a cathode, an anode, two 95 parallel grid electrodes interposed between said cathode and anode and connected together inside said envelope, and two separate electrostatic screens parallel to said grid electrodes, one of said screens being inter- 100

posed between said connected grid electrodes and the other of said screens being mounted outside said connected grid electrodes.

5. A thermionic tube comprising an envelope enclosing a cathode, an anode, two parallel grid electrodes interposed between said cathode and anode and connected together inside said envelope, and two separate electrostatic screens associated with said grid electrodes and mounted parallel to said grid electrodes between said cathode and said anode.

HENRY JOSEPH ROUND.
